[54] REPLACEABLE TIRE TREAD BELT

[75] Inventor: Marvin E. Beyers, Peoria, Ill.

[73] Assignee: Caterpillar Tractor Co., Peoria, Ill.

[21] Appl. No.: 880,668

[22] Filed: Feb. 23, 1978

[51] Int. Cl.² ..... B60C 11/00[52] U.S. Cl. 152/176; 152/188;
152/209 A

[57] ABSTRACT

A replaceable tire tread belt has outer and inner peripheral surfaces and a pair of opposite side surfaces. The inner peripheral surface has a plurality of projections

for interlocking engagement with a tire carcass, and the outer peripheral surface is axially divided into a smooth portion extending about the circumference and providing an extended service life, and a grooved portion extending about the circumference and defining the remaining portion of the outer peripheral surface and providing traction.
